UNITED STATES PATENT OFFICE.

GILBERT WRIGHT, OF PELHAM, NEW YORK.

ELECTROMAGNETICALLY-OPERATED VALVE.

1,284,021.

Specification of Letters Patent.

Patented Nov. 5, 1918.

Application filed March 15, 1917. Serial No. 155,071.

To all whom it may concern:

Be it known that I, GILBERT WRIGHT, a citizen of the United States, residing at Pelham, in the county of Westchester and State 5 of New York, have invented new and useful Improvements in Electromagnetically-Operated Valves, of which the following is a specification.

The present invention relates to valves 10 adapted to be located in conduits for the conveyance of fluid, and also to serve as the inlet and exhaust valves of steam engines, internal combustion motors, and the like, and in fact to be used anywhere that it 15 is desirable to interrupt and periodically permit, the flow of any liquid, gas, or vapor. The purpose of the invention is to provide an electromagnetic means for operating such valves; the particular utility of 20 such operating means in connection with the valve being that both the operating means and the valve may be contained in a closed chamber, whereby it becomes unnecessary to have any part of the valve or its operating 25 means pass through the wall of the conduit or chamber in which the valve is contained, and the opportunity for leakage of fluid, and the need for packing to prevent such leakage are avoided.

While the invention is applicable generally to any of the uses comprised within the broad statement of uses hereinbefore set forth, it is particularly adapted and available for controlling the admission of fuel, 35 and particularly liquid fuel, to an internal combustion motor, wherefore I have shown for the purpose of illustrating the invention an embodiment of the same which is particularly designed to serve this use. It is to 40 be distinctly understood, however, that this embodiment is so shown for the purpose of illustration only and without intent to indicate limitation of the invention to any specific mechanical form. In the drawings,

Figure 1 is a plan view of the cylinder of an internal combustion motor having a valve and its controller, in which my invention is particularly comprised, applied thereto.

Fig. 2 is a sectional view of the combined 50 apparatus taken on line 2—2 of Fig. 1.

Fig. 3 is a sectional view showing a modification of the armature.

I will describe in detail the specific embodiment here shown and then point out in 55 connection therewith the essential principles of the invention. 11 represents the cylinder

of an internal combustion motor into one head of which is screwed a nipple 12 on a case 13, to which is connected a detachable cover 14. Through the center of the nipple 65 and of the case 13 passes a core 15, the inner end of which is exposed to the interior of the cylinder, and the outer end of which is formed with a socket 16. Into said socket, the walls of which are threaded, is screwed 65 a plug 17, which likewise has a socket or recess containing a spring 18, and through the bottom of which is an opening 19. From the recess 16 a passage 20 leads longitudinally through the core 15 and terminates in a 70 valve cavity in the inner end of said core piece, which contains a valve 21 so formed as, when seated, to close the internal orifice of the passage 20. Said valve 21 is carried by a stem 22 which passes through the core 75 piece 15, through the plug 17, and carries on its end an armature 23 which is removably secured on said end. The spring 18 previously mentioned is confined between the armature and the bottom of the plug 17 and 80 presses constantly against said armature tending to seat the valve 21 and close the passage 20.

A pipe 24 is coupled by a coupling 25 to a nipple 26 on the cover 14, and through the 85 latter there is a small passage 27 opening into its interior. This passage 27, the space inclosed within the cover 14, the recess in the plug 17, the hole 19 from the bottom of said recess, the socket 16 in the core 15, and 90 the passage 20, provide a continuous conduit from the pipe 24 into the interior of the cylinder, said conduit being controlled by the valve 21.

The details of construction just described, 95 although they are preferred for the purposes of the specific use to which the invention is here shown as being applied, as being the simplest, most convenient, and most efficient construction which I have thus far devised 100 for this use, are not essential features of the invention, and I therefore do not limit my claim thereto. Various modifications in such details may be made, as may be readily appreciated. For example, the core need not 105 extend entirely through the case nipple, or any farther than necessary to complete the magnetic circuit, and it may be mounted and secured in place by other means. The valve seat need not be in the core itself, but may be 110 in the case nipple, or on some other part of the case or its cover; and the valve stem may

be guided by other means than the core, as by the nipple of the cover or by an extension of its upper end in the case, and the valve itself could readily be arranged to coact with 5 the inlet to the case rather than with the outlet therefrom. And instead of securing the case to the cylinder by means of a nipple, the latter could be omitted entirely and the case screwed directly to the cylinder, or attached 10 by external means such as bolts or studs. The essentials are simply that there must be a closed casing of some sort, suitable means of securing the same to a cylinder, pipe, or other connection with which the casing is 15 joined, a valve member with its coöperating seat, an electromagnet, and an armature coöperating with the magnet and arranged to operate the valve. The armature itself may serve as a valve in some cases, as hereinafter 20 pointed out, and then no other valve need be provided.

Inclosed within the case 13 and surrounding the core 15 is a magnet coil 28. The terminals 29 and 30 of this coil pass through 25 the side of the case through bushings of insulating material. Preferably a gasket 31 is arranged so as to cover the end of the coil and is clamped between the case 13 and its cover 14, and also between the core 15 and a 30 flange on the plug 17, the gasket being thus a fluid tight septum preventing access of the fluid to the coil or indeed to any part of the closed casing except the space which forms part of the conduit previously described.

35 It will be understood that by reason of the gasket, which of course is fluid tight at its inner and outer peripheries, the oil or other fluid is confined when the valve 21 is closed and is prevented from flowing anywhere except through the passage 20 into the cylinder 40 11 when the valve is open.

As the valve, coil, and the armature for the coil, which constitute the operating means for the valve, are all contained within 45 a closed case, it can very easily be made absolutely fluid tight, there is no opportunity for the oil or other fluid to leak to the exterior of the conduit, and therefore no need to provide any sort of packing for the valve 50 to prevent such leakage. Thus the valve may be made to operate more freely and easily than is possible where packing must be used, while the other inconveniences attendant upon a valve packing are avoided.

55 The gasket 31 is useful particularly to protect the coil 28 from whatever deleterious effects the oil or other fluid passing through the conduit might have on the coil if it were given access thereto. Where any such effects need not be considered the gasket may be omitted, and in such case the passages through which the leading-in wires to the coil pass would require to be sealed or otherwise made fluid tight in any well known, 60 65 or other suitable manner.

When the device as hereinbefore described is applied for the purpose of admitting liquid fuel to an internal combustion engine, a timing switch is provided to cause the opening of the valve at the desired instants 70 of time. Such switch comprises a stationary contact 32 and a movable contact 33; the former being connected with the terminal wire 30 of the coil and the latter being connected to a shaft 34 and embedded in a 75 disk 35 of insulating material fixed to the shaft. The stationary contact 32 passes through an insulating bushing 36 and is pressed by a spring 37 constantly against the face of the disk 35, being thereby caused to 80 make contact with the member 33 when the latter passes it. Shaft 34 is driven by the motor at the given rate of speed so as to cause the circuit to be closed at the required intervals. The complete circuit is shown in 85 a diagrammatic manner in Fig. 2, wherein a battery 38 is shown, one pole of which is connected with the magnet coil terminal 29, and the opposite pole is connected by a wire 39 with the metal cylinder or other metallic 90 part of the motor, through which the current is adapted to flow to the shaft 34 and thence to the switch contact 33. The battery 38 is merely typical of any source of 95 electrical energy and may be taken as representing a generating machine or a secondary battery as well as a primary battery of any desired sort.

With the foregoing description in mind the operation of the valve may be readily 100 understood, and it will be appreciated that whenever the switch contact 33 engages the contact 32, the armature 23 is attracted toward the pole of the coil, thereby opening the valve and allowing inflow of a quantity 105 of liquid fuel. When the armature is made imperforate as shown in Fig. 2 it is adapted by itself to serve as a valve by coming in contact with the end of the plug 17, the complementary surfaces of the plug and armature being then finished so as to make liquid-excluding contact. When used in the specific combination illustrated, the armature is a valve supplemental to the valve 21 and limits the quantity of liquid fuel injected into the cylinder at each operation. 110 For other purposes the said armature could be used alone as the valve, the valve 21 being then removed; or the armature can equally well be formed with apertures 115 as shown in Fig. 3 to permit passage of the fluid when it is brought against the plug 17 and the valve 21 is opened, then having no valve function whatever.

It will also be understood that various 120 modifications in form and arrangement of the elements of the device may be made to adapt the same to the various uses which the invention is capable of serving. I claim within the scope of the protection here 125 130

sought, all such modifications provided they embody the essential features set forth in the claims.

What I claim and desire to secure by Letters Patent is:

1. A valve comprising essentially a casing having an inlet and an outlet, a magnet winding contained in said casing, a core surrounded by said winding having a passage 10 between said inlet and outlet, a septum or gasket extending over said winding to exclude therefrom the fluid passing through the casing and being made fluid-tight at the casing wall and at the core, an armature 15 operating with said magnet winding and core, and a valve arranged to open and close said outlet and being connected with the armature to be operated thereby, said armature serving as a valve, and the core having 20 a complemental seat surrounding the entrance to the passage therethrough, with which the armature is adapted to coöperate in closing such passage.

2. An electromagnetic valve comprising 25 a casing having a nipple at one end, a core set in said nipple, a cover secured to said casing, an electromagnet coil in the annular space between said core and the casing wall, the core having a socket in the end opposite 30 to said nipple and having a passage communicating with said socket, a plug secured in said socket and also having a passage communicating therewith, a gasket secured at its outer end between the casing wall and 35 the cover and at its inner edge between the end of said core and said plug, a valve arranged to obstruct the passage in said core, said valve having a stem guided to move in the core, and an armature secured to said 40 stem in position to be attracted by the magnetic force generated by the winding, and means for conducting fluid to and through said cover.

3. An electromagnetic valve comprising 45 a casing having a nipple at one end, a core set in said nipple, a cover secured to said casing, an electromagnetic coil in the annu-

lar space between said core and the casing wall, the core having a socket in the end opposite to said nipple and having a passage 50 communicating with said socket, a plug secured in said socket and also having a passage communicating therewith, a gasket secured at its outer end between the casing wall and the cover and at its inner edge between the end of said core and said plug, a valve arranged to obstruct the passage in 55 said core, said valve having a stem guided to move in the core, and an armature secured to said stem in position to be attracted by the magnetic force generated by the winding, and means for conducting fluid to and through said cover, the terminals of 60 said core passing through the walls of said casing.

4. An electromagnetic valve comprising 65 a casing having a nipple at one end, a core set in said nipple, a cover secured to said casing, an electromagnetic coil in the annular space between said core and the casing wall, the core having a socket in the end opposite to said nipple and having a passage 70 communicating with said socket, a plug secured in said socket and also having a passage communicating therewith, a gasket secured at its outer end between the casing wall and the cover and at its inner edge between the end of said core and said plug, a valve arranged to obstruct the passage in 75 said core, said valve having a stem guided to move in the core, and an armature secured to said stem in position to be attracted by the magnetic force generated by the winding, and means for conducting fluid to and through said cover, the terminals of said 80 core passing through the walls of said casing, and a switch in circuit with said terminals and with a source of electrical energy for causing electrical energy to pass through 85 said coil.

In testimony whereof I have affixed my signature.

GILBERT WRIGHT.
